UNITED STATES PATENT OFFICE

ROBERT G. BRUCE, OF MEMPHIS, TENNESSEE, ASSIGNOR TO E. L. BRUCE COMPANY, OF MEMPHIS, TENNESSEE, A CORPORATION OF DELAWARE

WOOD BLOCK FLOOR

Application filed May 27, 1929. Serial No. 366,338.

My invention relates to wood block floors and one of the objects is to provide a floor of this type that will have some of the characteristics in appearance of a tile floor and in which the outline of each block will be brought out in relief.

A further object is the production of a block that can be completely finished at the factory so that after it is laid in position in the floor, it will require no further surface finishing at the time of laying and there will be no apparent unevenness in the floor.

With these and other objects in view, my invention consists in certain novel and peculiar features of construction and combination of parts as will be hereinafter more fully described and particularly pointed out in the claims.

Referring to the drawings for a more complete disclosure of the invention:

Fig. 1 is a plan view of a fragment of a floor;

Fig. 2 is a section on the line 2—2 of Fig. 1;

Fig. 3 is a perspective view of a block; and

Fig. 4 is a bottom plan view of a block.

The blocks that are used are preferably made from a plurality of strips of wood, 10, with the grain running lengthwise. The strips are joined along their longitudinal edges by the customary tongue and groove joint 11. For holding the strips of the block tightly in assembled relationship, a metal tie 12 has its edges 13 forced into biting engagement with the sides of the groove 14. For uniting one block with the adjacent block in the production of the floor, I use a suitable cooperating tongue and groove relationship on the adjacent blocks, that shown comprising a tongue 15 along one longitudinal edge of the block and a similar tongue 16 along one transverse edge of the block, the adjacent corners being cut away at 17. Along the other longitudinal edge is a groove 18 and along the other transverse edge is a groove 19.

It will be clear that when the blocks are laid in position on the subfloor 20 that the tongue 16 engages a groove on an adjacent block located similar to the groove 18 and that the tongue 15 engages a groove on an adjacent block located similar to the groove 19.

The blocks can be laid on the subfloor 20 and held in position by means of a non-setting plastic cement 26. The strips 10 are provided on their underside with a suitable "hollow-back" 21. Between the strips 10, the customary "relief" 22 may be provided. The tongue and groove connection 11 is the conventional one, except that the abutting faces 23 are preferably at right angles to the face of the strips.

After the block has been fabricated, it is treated with a suitable oleaginous impregnating composition to make the wood moisture resistant.

The upper edges of each block are bevelled off at 24. When the blocks are laid in the floor this will provide a groove or depression 25 around each block that will be about one-eighth of an inch across and of about the same depth.

The blocks, having been made and the edges bevelled off, are then individually finished by sanding, scraping, waxing, polishing, and coloring if desired.

That is to say, instead of laying the blocks in the condition of finish in which flooring is ordinarily laid, I do all the surface finishing before laying the blocks, and at the factory. A floor layer has merely to lay the blocks in position and the floor is immediately ready for use.

Due to the fact that the blocks are sanded and scraped individually, there will be a slight difference in thickness. If the edges of the blocks are square, any slight difference in the thickness of the blocks is immediately apparent where two square edges are brought sharply together. There may be

other causes of slight unevenness than that due to varying thicknesses of the blocks. The elimination of the square edges by the use of the groove 25 permits of slight inequalities in the level of adjacent blocks without being readily apparent to the eye.

The presence of the groove or depression around each block also produces a desired optical effect by virtue of the shadow that is cast on the sides of certain of the grooves, depending of course on the direction of the light that is cast on the floor.

The grooves cause the blocks to stand out in relief producing somewhat the effect of tiles. They also break up the plane reflecting surface that is present where the edges of the blocks are square.

In order to further bring out the tile effect, I may stain the blocks at the factory with stains of various colors as a part of the finishing operation and then lay the floor with blocks of contrasting colors. As shown in Fig. 1 the blocks 26 may be green and the blocks 27 may be red.

25 The size of a floor block has an effect on the apparent size of a room. Small blocks in a small room will make the room appear larger than would be the case if larger blocks were used. Bringing into relief and making 30 distinctive, the particular size of the block, by means of the shading that is produced by the groove enhances the effect of the size of the blocks.

After the floor has been in use, it may be 35 desirable to recolor the blocks. This can be done neatly by using a stencil having an opening the size of the block and in which the downturned edges of the opening in the stencil will fit in the V-grooves 25, thus preventing 40 the color on the brush from getting on an adjacent block of a different color.

I claim:

1. A panel formed of wood blocks having their sides in abutting relationship, the grain 45 of the wood of adjacent blocks being at an angle to each other and running in the same plane as the face of the block, open grooves surrounding the faces of the blocks, the said grain and grooves bringing into relief the 50 outline of each block.

2. A panel formed of wood blocks of contrasting colors and having their sides in abutting relationship, the grain of the wood of adjacent blocks being at an angle to each 55 other and running in the same plane as the face of the block, open grooves surrounding the faces of the blocks, the said colors, grain and grooves bringing into relief the outline of each block.

60 3. As a new article of manufacture, a wood block, the face of the block being provided with a final surface finish before laying the block in position for use in a panel, all the face edges of the block being bevelled, the 65 block being formed of a plurality of strips,

with the grain of the wood running lengthwise of the strips.

4. As a new article of manufacture, a wood block, the face of the block being provided with a final surface finish before laying the block in position for use in a panel, all the face edges of the block being bevelled and the grain of the block running in the same plane as the said face.

In testimony whereof I affix my signature. 75
R. G. BRUCE.
